CLAIM

(52) **U.S. Cl.**

The ornamental design for a rotating electrosurgical hand piece, as shown and described.

USPC **D24/144**

DESCRIPTION

(58) **Field of Classification Search**

USPC D24/133, 144, 146–147; D8/83, 107; 200/332.2; 606/1, 32, 39–42, 45, 606/169–170

See application file for complete search history.

(56) **References Cited**

FIG. 1 is a side perspective view of the rotating electrosurgical hand piece of the medical instrument, showing my new design;

U.S. PATENT DOCUMENTS

FIG. 2 is a front view thereof;

FIG. 3 is a rear view thereof;

FIG. 4 is a top view thereof;

FIG. 5 is a bottom view thereof; and,

FIG. 6 is a left side view thereof, the right side view (not shown) being a mirror image of the left side view.

The broken lines are included for the purpose of illustrating environmental structure and form no part of the claimed design.
